UNITED STATES PATENT OFFICE.

HARVEY M. GERSMAN, OF CHICAGO, ILLINOIS.

PRODUCTION OF EXPANDED SHEET METAL (HERRINGBONE TYPE).

Application filed June 1, 1923. Serial No. 642,873.

To all whom it may concern:

Be it known that I, HARVEY M. GERSMAN, a citizen of the United States, residing at Chicago, in the county of Cook and State 5 of Illinois, have invented a new and useful Improvement in the Production of Expanded Sheet Metal (Herringbone Type), of which the following is a specification.

This invention relates to the production 10 of expanded sheet metal and its principal object is to provide a method of simple character for the production of expanded sheet metal having novel structural features and superior qualities, such expanded metal 15 forming the subject of my co-pending application Serial No. 642,872.

"Herringbone" is the name applied to a form of expanded metal lathing which is characterized by parallel webs and by 20 spaced parallel strands extending between and connecting the adjacent webs. In so far as expanded metal produced by the method of the present invention conforms to these broadly stated characteristics of herringbone metal it may be conveniently designated as of the herringbone type.

The manner of practicing the invention will be apparent from the accompanying drawings, taken in connection with the description which follows.

In said drawings:

Figure 1 is an elevation of the outer or observe face of a fragmentary portion of either a single or double sided sheet expanded by the method of the present invention.

Figure 2 is a cross sectional view on the line 2-2 of Figure 1.

Figure 3 is a longitudinal sectional view on the line 3-3 of Figure 2.

Figure 4 is an elevation showing an initial stage in the formation of the blank for a single-sided sheet.

Figure 5 shows the blank ready for expansion.

Figure 6 is a section on the line 6-6 of Figure 5.

Figure 7 is a cross section of the blank shown in Figure 5.

Figure 8 is an elevation of the outer or obverse face of a fragmentary portion of the sheet expanded from the blank of Figure 5, and is drawn to a scale conforming to the scale of Figures 4 to 7.

Figure 9 shows the blank for a double-sided sheet.

Figure 10 is a section on the line 10-10 of Figure 9.

Figure 11 is a cross section of the blank shown in Figure 9.

Referring to Figures 1, 2 and 3:

These figures illustrate a fragment of an expanded metal sheet having parallel imperforate portions or webs 12 and expanded portions between the imperforate portions, the expanded portions being characterized by spaced parallel strands 13 which preferably extend diagonally between the adjacent webs.

The strands 13 of each expanded portion lie flat in a common plane and the connections by which they are joined to the adjacent webs are disposed at the same, that is to say corresponding, sides of said webs which, as parts of lathing, also lie flat in a common plane.

The connections between the strands and the webs include portions 14, which are offset from the webs in planes normal to the common plane of the strands. The common plane of the strands is preferably offset from and parallel to the common plane of the webs, the offsets 14 determining the elevation of the strands relatively to the webs.

The offsets 14 are arranged at the sides of the webs and along each side provide, in functional effect, a rib parallel to the web and which re-inforces the sheet in the longitudinal direction, considering the webs as extending lengthwise of the sheet.

The strands have at their ends angular portions 15 which extend from the offsets 14 and may be regarded as angular extensions of the offsets, the portions 15 being delimited by breaks, i. e., lines of bending, 16 and 17 which extend at angles to one another from the corners of the offsets remote from the webs.

The breaks 16 lie in the plane of the offsets and extend to the webs, forming

- the common bases of polygons which are delimited by the offsets and their angular extensions 15, such polygons being triangular in the preferred construction disclosed.
- 5 The breaks 17 lie in the planes of the strands and provide a series of ribs which re-inforce the expanded portions of the sheet in generally transverse directions, that is to say directions at an angle to the lengthwise direction of the webs.

Figures 1, 2 and 3 show two adjacent webs 12 and an expanded portion between them and it will be understood that the fragment shown may be regarded as either of 15 a single sided sheet or a double sided sheet. In a single sided sheet all of the expanded portions are arranged at the same, i. e., corresponding, sides of the webs; such a sheet being completely self furring. In a double 20 sided sheet the expanded portions are arranged alternately at opposite sides of the webs. The strands preferably extend diagonally and may extend all in the same direction or, as preferred, in the alternate expanded portions they may extend in opposite directions.

The method is practiced in connection with a slotted blank which in all cases is formed whereby in the expanded sheet the 30 bends or breaks at both ends of each strand will occur at corresponding sides of the adjacent webs and in relation to offsets lying in planes substantially normal to the plane of the strand and whereby by a single expansion or stretching of the blank in a direction of its mean plane the sheet is produced in completed form with its webs in a common plane and the strands of each expanded portion in a common plane, preferably offset from and parallel to the common plane of the webs.

The specific structure disclosed may, as embodied in single sided sheets, be produced from the blank shown in Figures 5, 6 and 7 45 and as embodied in double sided sheets be produced from the blank shown in Figures 9, 10 and 11. It will be understood however that the illustration of the blanks and the description to follow of the method of expansion is not to be taken as imposing limitations to the exact form of blank illustrated or to the exact details of the method described, since within the limits of the invention variations may be incorporated in 50 the form of the blank as regards the outline and arrangement of the slits and details of the method as regards the distortion of the blank incident to the expansion.

Referring to Figures 4, 5, 6 and 7:

60 The blank is produced from a sheet of flat metal formed with rows of slits 18 (Figure 4), the slits of each row delimiting the area in which expansion is effected and the imperforate spaces 19 between the rows of 65 slits being available for the webs. The slits

are similarly arranged and each terminates at differently located points along the edges of the imperforate portions between which it extends. As shown the slits are arranged diagonally, extending in opposite directions 70 in the alternate rows. The flat sheet provided with the slits, as described, is then longitudinally corrugated to provide the completed blank shown in Figures 5, 6 and 7. The longitudinal corrugations are alternately inverse and consist of corrugations 20 presenting channels to the obverse face of the blank and corrugations 21 presenting channels to the reverse face of the blank. The adjoining inverse corrugations have 80 common sides which are struck up along the opposite sides of the slotted portions whereby, in the embodiment disclosed, the slits 18 extend throughout the bases and sides of the corrugations 21. The completed blank is 85 then expanded or stretched in a direction of its mean plane. With the specific form of blank disclosed the alternate portions 19 are rotated in the same direction in their common plane with reference to the remaining 90 portions 19 which are held against rotation. In case all of the slits of the blank should extend in the same direction (as where it is desired to have all of the strands extend in the same direction) the blank is held at one 95 side only and all of the remaining portions 19 are rotated in the same direction but in relative succession, a step-by-step rotative effect being thus obtained. The stretching of the blank in the above manner will result 100 in expanded metal having the characteristics described, a larger fragment drawn to the scale of Figures 4 to 7 being shown in Figure 8. In connection with the expansion of the blank disclosed the portions of metal 105 which provide the sides of the corrugations 21 are utilized for the offsets 14 and extensions 15. This will be apparent by reference to Figure 6 from which it will be observed 110 that the sides of the corrugations are made of uniform conterminous portions, each of rhomboidal outline, whereof the pairs of adjacent sides which form the acute angles are the sides of the triangles delimited by the offsets 14 and the extensions 15, the sides 115 which adjoin the bases of the corrugations 21 coincide with the breaks 17, and lines taken as common interceptors of the obtuse angles coincide with the breaks 16 developed during the expansion.

120 Referring to Figures 9, 10 and 11:

In this case the blank is formed with longitudinal corrugations 21^a and 21^b corresponding functionally to the longitudinal corrugations 21 of the preceding example but formed alternately inversely and at the opposite sides of the co-planar imperforate portions 19 by which the sides of the adjacent inverse corrugations are connected, the slits 18, as before, being extended through 130

the sides of the corrugations to the imperforate portions. The methods of expansion is precisely the same as in the preceding example but the form of the blank results in 5 double sided expanded sheets, that is to say sheets wherein the strands 13 of alternate expanded portions lie at opposite sides of the webs 12.

Having fully described my invention, I 10 claim:

1. The method of producing expanded metal from a flat sheet having parallel imperforate portions and a row of similarly arranged slits between each pair of adjacent 15 imperforate portions, each slit terminating at differently located points along the edges of the imperforate portions between which it extends, which consists in corrugating the slotted sheet to form a complete blank 20 and in expanding the blank by the application of stretching force in a direction of its mean plane and wherein the corrugations of said blank are arranged in the directions of said imperforate portions and are so 25 formed and related to said imperforate portions and slits that upon the application of the stretching force the imperforate portions will be produced as spaced parallel webs and the portions of the metal between 30 the slits will be produced as strands lying flat in a common plane and bent from offsets located at corresponding sides of said webs in planes normal to the common plane of said strands.
- 35 2. The method of producing expanded metal from a flat sheet having parallel imperforate portions and a row of similarly arranged slits between each pair of adjoining imperforate portions, each slit terminating at differently located points along the edges of the imperforate portions between which it extends, which consists in corrugating the slotted sheet to form a complete blank and in expanding the blank by the 40 application of stretching force in a direction of its mean plane and wherein the corrugations of said blank are arranged in the directions of said imperforate portions and are so formed and related to said imperforate portions and slits that upon the application of the stretching force the imperforate portions will be produced as spaced parallel webs lying flat in a common plane and the portions of the metal between 45 the slits will be produced as strands lying flat in a common plane and bent from offsets located at corresponding sides of said webs in planes normal to the common planes of the webs and strands.
- 50 3. The method of producing expanded metal from a flat sheet having parallel imperforate portions and a row of similarly arranged slits between each pair of adjoining imperforate portions, each slit terminating at differently located points along the edges of the 55 imperforate portions between which it extends, corrugating the sheet along the slotted portions, the corrugations being parallel to the imperforate portions and the slotted portions providing the bases and sides of the corrugations and expanding the corrugated slotted sheet by the application of stretching force in a direction of the mean plane of the sheet.
- 60 4. The method of producing expanded metal from a flat sheet which consists in cutting the sheet with rows of slits, leaving parallel imperforate portions between the slits, the slits of each row being similarly arranged and each slit terminating at differently located points along the edges of the imperforate portions between which it extends, corrugating the sheet along the slotted portions, the corrugations being parallel to the imperforate portions and the slotted portions providing the bases and sides of the corrugations and expanding the corrugated slotted sheet by the application of stretching force in a direction of the mean plane of the sheet.
- 65 5. The method of producing expanded metal from a flat sheet which consists in

the edges of the imperforate portion between which it extends, which consists in corrugating the sheet along the slotted portions in a direction parallel to the imperforate portions to form a complete blank, 70 the sides of the corrugations extending from the imperforate portions and the slits extending to the imperforate portions through said sides, and in expanding the blank by the application of stretching force to rotate 75 the imperforate portions relatively to one another in their common plane whereby the imperforate portions will be produced as spaced parallel webs lying flat in a common plane and the portions of the metal between 80 the slits will be produced as strands lying flat in a common plane and bent from offsets located at corresponding sides of said webs in planes normal to said common planes of the webs and strands, the common plane of the strands being offset from and parallel to the common plane of the webs.

4. The method of producing expanded metal from a flat sheet having parallel imperforate portions and a row of parallel 90 diagonal slits between each pair of adjoining imperforate portions, which consists in corrugating the sheet along the slotted portions in a direction parallel to the imperforate portions to form a complete blank, 95 the sides of the corrugations extending from the imperforate portions and the slits extending to the imperforate portions through said sides, and in expanding the blank by the application of stretching force to rotate 100 the imperforate portions relatively to one another in their common plane whereby the imperforate portions will be produced as spaced parallel webs lying flat in a common plane and the portions of the metal between 105 the slits will be produced as strands lying flat in a common plane and bent from offsets located at corresponding sides of said webs in planes normal to said common planes of the webs and strands, the common plane of the strands being offset from and parallel to the common plane of the webs.

5. The method of producing expanded metal from a flat sheet which consists in cutting the sheet with rows of slits, leaving 110 parallel imperforate portions between the slits, the slits of each row being similarly arranged and each slit terminating at differently located points along the edges of the imperforate portions between which it extends, corrugating the sheet along the slotted portions, the corrugations being parallel to the imperforate portions and the slotted portions providing the bases and sides of the corrugations and expanding the corrugated slotted sheet by the application of stretching force in a direction of the mean plane of the sheet.

6. The method of producing expanded metal from a flat sheet which consists in

cutting the sheet with rows of slits, leaving parallel imperforate portions between the slits, the slits of each row being similarly arranged and each slit terminating at different located points along the edges of the imperforate portions between which it extends, corrugating the sheet along the slotted portions, the corrugations being parallel to the imperforate portions which are

left flat and the slotted portions providing the bases and sides of the corrugations and expanding the corrugated slotted sheet by the application of stretching force in a direction of the mean plane of the sheet.

In testimony whereof I affix my signature.

HARVEY M. GERSMAN.
